RAIL AND SUPPORT FOR THE SAME

Application filed February 5, 1931. Serial No. 513,550.

This invention relates to rails for railway track or the like and to means for supporting rails. More particularly, the invention is characterized by the provision of a rail with reversible heads symmetrically arranged at the ends of a connecting web portion and the provision of supports in the form of clamp members disposed at opposite sides of the rail and adapted to grip the rail therebetween to maintain it in vertical position and at a predetermined height above the underlying ties.

The object of the invention is to reduce the maintenance cost of rails by providing a double headed rail which is adapted to be supported in any one of four positions and which when worn may be reversed with respect to its supports so as to present new surfaces at the gage side, the reversal being accomplished either by rotation of the rail about its longitudinal axis, in which case the under side becomes the top, or by rotation about a vertical axis, in which case the inner side becomes the outer side.

Heretofore it has been proposed to use double headed rails in combination with clamp members bearing against and secured to the rail at its web portion. With the present invention, the areas of contact between the supporting clamp members and the rail are confined to the inclined surfaces on the inner sides of the rail heads so that as wear takes place at these surfaces the clamp members can be drawn closer together, whereby the rail may be effectively supported at all points of its length and in proper alignment with adjoining rails.

A further object of the invention is to provide supporting members arranged at opposite sides and adapted to bear upon and to support the double headed rail at the inner surfaces of the rail heads, together with means for drawing the supports together to grip the rail and means on the underlying foundation affording abutments to prevent the rail supports from spreading apart.

Other objects and advantages characterizing the invention will become more fully apparent from the detailed description which follows hereinafter, and which has reference to the accompanying drawings, whereof:

Fig. I is a plan view of a portion of a double headed rail supported in the manner of our invention; and,

Fig. II is a cross section of the same.

In the drawings a double headed rail is shown at 1, the rail comprising reversible heads 2 and 3 disposed symmetrically at the ends of a connecting web portion 4. Each head 2 and 3 is joined to the web portion 4 in a manner similar to that in which the heads or ordinary rails are joined to the webs. The rail 1 is maintained in vertical position by means of supports 5 arranged at opposite sides of the rail web 4. Each support 5 comprises a flat base 6 and upright clamp members 7 forming an angle with the base 6 and terminating in inclined bearing surfaces 8 and 9 which engage the inner surfaces 10 and 11, respectively, of the rail heads 2 and 3; i. e., the surfaces where the rail heads 2 and 3 join the web portion 4. The flat base 6 of each support 5 is provided with an extension 12 which projects beneath the rail head 3, the head occupying the downward position, to a point near the center thereof. The upright members 7 form in effect opposed clamp members between which the rail 1 is firmly gripped. Both the rail 1 and the clamp members 7 are perforated throughout their lengths, and when these perforations have been aligned, bolts 13 are passed therethrough, the bolts and their nuts 14 serving as means for drawing together the opposed clamp members to grip the rail 1. On the bolts 13, lock washers 15 may be employed to more effectively prevent loosening of the nuts 14. The portion 16 of each clamp member 7, which is intermediate the inclined surfaces 8 and 9 bearing upon the reversible heads of the rail 1, is preferably of a cross-sectional shape somewhat resembling that of a joint bar; and it is concaved on the inside as shown at 17. The clamp members 7 being so formed, when the nuts 14 are tightened on the bolts 13, the web 4 of the rail 1 is not engaged by the clamp members. In fact, the rail is entirely supported by the engagement of the inclined surfaces 8 and 9 of the clamp members with the inner surfaces 10 and 11 of the rail. Accordingly, such wear as may take

place on the clamp members 7 can be taken care of by periodic tightening of the nuts on the bolts 13.

Beneath the rail supports 5 there are tie plates 18 arranged in pairs, as shown in Fig. 5, there being two tie plates to each tie 20. Each tie plate is secured to the underlying tie 20 by spikes 21 passing through suitable perforations in the ends of the tie plate. At one end of each tie plate 18 there is punched out from the plate a shoulder 19 which is bent to the form of a hook, and the two tie plates of each pair are so arranged that their shoulders 19 are in opposed relation. The shoulders 19 afford abutments engaging the outer edge of the rail supports 5 and prevent them from lifting or spreading apart, thus assisting their function of maintaining the rail 1 in a vertical position suspended at a predetermined height above the tie plates.

Obviously the form of the shoulders 19 or such other abutments as may be provided to prevent spreading of the rail supports 7 admits of considerable variation, and while we have referred to the member 18 as a "tie plate", it will be understood that the spaced abutments for preventing the spread of the clamp members may be provided on many forms of tie plates, ties, or foundations for the rails. The double headed rails described above are preferably rolled in lengths as long as commercially practicable, and likewise the rail supports are also preferably rolled in lengths as long as practicable and are joined together at their ends by suitable splicing members which form no part of this invention.

It will be apparent from the description thus far that the rail 1 may be reversed to present four different wearing surfaces at the gage side. By reversing the rail, either through rotation about its longitudinal axis, in which case the head 2 occupies the under side and the head 3 the upper side, or by rotation about a vertical axis, in which case the head 2 remains at the top but the gage side is changed, the surface upon which wear takes place incident to the passage of rolling stock may be renewed periodically. Any tendency of the rail 1 to be deflected from its normal vertical position is opposed by the relatively wide flat bases 6 of the supporting members 7.

The material selected for the heads of the reversible rail of this invention is preferably an alloy, or plain carbon steel, heat treated, of such quality and temper to withstand high unit loading pressures without detriment to the rail heads.

Furthermore, it will be particularly noted that the supports 5 are so formed and disposed with relation to the reversible rail 1 that with the exception of the areas at the inclined bearing surfaces 8 and 9, there is substantial clearance between the rail supports

5 and the rail 1. Ample space is provided between the base portions 12 of the supports 5 and the downturned head 3 of the rail 1. Inasmuch as the engagement between the rail and its supports is confined to the areas at the inner sides of the heads 2 and 3, such variations in the dimensions of the rail as result from allowed tolerances in rolling or from distortion of the rail in service, do not materially affect the proper positioning of the rails at a predetermined height above the ties, nor the alignment of one rail with another, nor the position of the tread of a rail where the heads have been reversed.

While we have described our invention in some detail and with reference to a particular form of rail and supporting members therefor, it will be apparent that changes may be made in the form of the structures disclosed without departing from the spirit of our invention as defined in the annexed claims.

Having thus described our invention, we claim:

1. In combination, a rail having a web portion and heads symmetrically disposed at each end of said web portion, supports for said rail in the form of clamp members bearing on the inner surfaces of said rail heads at opposite sides but elsewhere clear of the rail heads, and clear of the rail web so that as wear occurs they may be drawn closer together, and means for securing said clamp members together with the rail gripped therebetween.

2. In combination, a rail having a web portion and reversible heads disposed at each end of said web portion, supports comprising flat bases with upright clamp members adapted to engage the inner surfaces of the rail heads at opposite sides but elsewhere clear of the rail heads, and clear of the rail web so that as wear occurs they may be drawn closer together, and means for securing the clamp members of said supports together with the rail gripped therebetween, said means passing through the rail web.

3. In combination, a rail having a web portion and reversible heads disposed at each end of said web portion, supports comprising flat bases with upright clamp members adapted to engage the inner surfaces of the rail heads at opposite sides, and said clamp members being clear of the rail at all other points so that as wear occurs they may be drawn closer together, and bolts passing through the rail web for securing the clamp members of said supports together with the rail gripped therebetween.

4. In combination, a rail having a web portion and reversible heads at each end of said web portion, supports for said rail comprising flat bases with upright clamp members having inclined bearing surfaces adapted to engage the inner surfaces of the rail heads at opposite sides but elsewhere clear of

the rail heads, and said clamp members having intermediate said inclined bearing surfaces concaved inner surfaces clear of the rail web so that as wear occurs they may be drawn closer together, and means for securing said clamp members together with the rail.

5. In combination, a rail having a web portion and reversible heads disposed at each end of said web portion, supports comprising flat bases with upright clamp members thereon, said clamp members having inclined surfaces adapted to bear upon the inner sides of the rail heads and said clamp members being clear of the rail at all other points so that as wear occurs they may be drawn closer together, and bolts passing through the rail web for securing said clamp members together with the rail gripped therebetween.

10. In combination a rail having a web portion and reversible heads disposed at each end of said web portion, supports comprising flat bases with upright clamp members thereon, said clamp members having inclined surfaces adapted to bear upon the inner sides of the rail heads with substantial clearance between the web of the rail and the inner sides of said clamp members whereby said members may be drawn closer together as 15 wear occurs, bolts passing through the rail web for securing said clamp members together with the rail gripped therebetween, and tie plates beneath said rail supports, said tie plates having hook-shaped abutments 20 thereon at opposite sides of the rail for preventing said clamp members from lifting or spreading apart.

In testimony whereof, we have hereunto signed our names at Philadelphia, Pa., this 25 19th day of January, 1931.

CHARLES D. YOUNG.
ARTHUR B. CLARK.
